METHOD FOR PACKAGING SAUSAGE PATTIES

Ray F. Beerend, 845 State St., Vermilion, Ohio

Original application Jan. 20, 1955, Ser. No. 482,969, now Patent No. 2,814,921, dated Dec. 3, 1957. Divided and this application Apr. 22, 1957, Ser. No. 654,325

3 Claims. (Cl. 99—174)

This invention relates to a method for packaging sausage patties or the like.

The present application is a division of my copending application Serial No. 482,969, filed January 20, 1955, now United States Patent 2,814,921, which is a continuation-in-part of my application Serial No. 384,200, filed October 5, 1953, now abandoned.

Using a conventional sausage stuffing machine as a means for supplying the plastic sausage meat under pressure, I receive the meat into the openings of a mould slide as the slide reciprocates over the meat supply port. The openings will be filled in the retracting movement of the slide.

At the extreme position of advance of the slide, it is allowed to dwell over the uppermost carton blank in a stack of blanks. While the slide dwells over the stack blanks, a group of ejector dies descends through the openings of the slide to eject the individual patties onto the top blank of the stack.

Whereas the device of my former application 384,200 was manually operated, the present device operates automatically to complete a single cycle each time the control lever is tripped by the operator. In addition, there are specific improvements in the packing for the mould slide. No claim is made in the present application to the pneumatic control valves per se.

The pressure support for the carton blanks holds the uppermost blank in the stack against a stop at a spacing which is below the slide to an extent which is at least equal to the thickness of the individual patties. Hence, as soon as the ejector dies are retracted from the slide, the slide is free of the deposited patties for retraction across the filling zone to initiate another cycle of operations. Meantime the carton blank with the patties deposited thereon is withdrawn and flaps thereof constituting the sides, ends and bottom of the carton are folded over the patties to complete the enclosure thereof. The finished carton is then turned to upright position. The panel portion upon which the patties are deposited is actually the top of the finished carton. It is desirably windowed so that the patties enclosed in the carton are displayed through the window.

In the drawings:

Fig. 1 is a plan view of apparatus embodying the invention.

Fig. 2 is a view in side elevation of the device shown in Fig. 1.

Fig. 3 is a view taken in section on the line 3—3 of Fig. 1.

Fig. 4 is a view of the device in end elevation, portions being broken away.

Fig. 5 is an enlarged detail view taken in section on the line 5—5 of Fig. 3.

Fig. 6 is a fragmentary detail view taken in section on the line 6—6 of Fig. 5.

Fig. 11 is a fragmentary view of the mould slide in perspective.

Fig. 12 is a fragmentary view of a modified embodiment of the mould slide as it appears in perspective.

Fig. 13 is a view in perspective showing the workpieces embodied on the carton forming blank.

Fig. 14 is a view of the completed carton as it appears in perspective.

My device is designed as an attachment for the filling nozzle 9 of a sausage stuffing machine which is adapted to supply sausage meat under pressure, as from a feed screw (not shown). To the nozzle 9, I attach the pressure head 10 of my apparatus by means of cap screws 11 or the like.

The pressure head 10 is carried by a plate 12 as best shown in Figs. 3 and 5. This plate fits closely between the upstanding flanges 13, 14 of a base member 15 supported by legs 16, 17. Screwed to the upper margins of flanges 13, 14 are plates 18, 19, 20, 21 (Figs. 1, 5 and 6, respectively) carrying set screws 23 adjusted into pressure engagement with pads 24 in the cover plate 12 to exert any desired downward pressure on plate 12. In addition, the plates 18, 19 are provided with headed dowel pins 25 engaged in sockets 26 of the cover plate 12 and manually withdrawable from such engagement against compression of springs 27 (see Fig. 6).

Under pressure of the set screws 23, the plate 12 tightly engages the upper surface of the mould slide 30 which is reciprocable in the channel provided by the base member 15 and its upstanding flanges 13, 14. An appropriate liner is desirably provided at 31 to minimize the friction between the slide 30 and the base member 15. The liner is positioned by upstanding lateral flanges 32, 33 and depending end flanges 34 which engage the ends of the base member 15 as best shown in Fig. 3 and Fig. 6.

The liner or packing sheet 31 may be of any appropriate material. I have found "Bakelite" to be a good material for the purpose, as it not only provides tight packing but reduces friction in the movement of the slide.

The slide 30 is provided with mould openings at 35 in which the workpieces are formed as the material is delivered under pressure through the pressure head 10 into the openings when the slide is retracted to the position shown in Fig. 3 so that the openings register with the head. A cavity is provided at 36 in the pressure plate 12 around the opening from the head to receive a packing sheet 37 which has openings registering with the openings 35 of the slide as best shown in Fig. 3, and has beveled margins at 38 around each such opening so that the pressure of the material supplied through the pipe 9 to the pressure head 10 is directed against this beveled surface to hold the packing member 37 in intimate pressure engagement with the upper surface of slide 30.

The slide 30 and the correspondingly apertured packing member 37 (as well as the ejector dies) are readily interchangeable when it is desired to make workpieces of different dimensions. An alternatively usable slide is fragmentarily illustrated at 300 and it will be observed that the openings 350 therein are quite radically different in size and shape from the openings 35 in slide 30 as shown in Fig. 11. It will be understood that for each type of opening provided in slide 30 there will be a correspondingly apertured packing member 37 desirably having, in all instances, beveled margins at 38 about the openings therein provided.

Dismantling of the machines for cleaning or for the interchange of slides, requires only a few moments, since

the retraction of the dowel pins 25 permits the pressure plate 12 to be slid from beneath the set screw 23, whereupon the slide is completely accessible and may be freely removed upon separation from the slide-actuating mechanism presently to be described.

As explained in application 384,200, the retracted slides 30 or 300 receive a charge of material from the pressure head 10 when the slide openings 35 register with the head at the corresponding ports in the packing member 37. As the slide advances from the retracted position shown in Fig. 3 to the delivery position shown in Fig. 1, its apertures register with the normally elevated expulsion dies 40 which are carried by a cross head 41 mounted on plunger 42. As these dies descend from the elevated position in which they are shown in Figs. 2 and 3 to the lowered position of Fig. 4, they pass through the openings 35 in the mould slide 30 (or 300) to expel the workpieces 45 therefrom.

In the preferred embodiment of the invention, windowed carton blanks 46 are mounted, face down, in a pile on the spring-supported table 47. This table is carried by parallel links 48, 49 and is biased upwardly by spring means at 50 (Fig. 3). Suitable guide arms 52, 53 hold the carton blanks in registry to receive the several workpieces on their inner windowed surfaces as best shown in Fig. 13. When the end walls 54, 55 and the side walls 56, 57 of the blank are erected and the back flaps 58, 59 interlock about the workpieces or patties 45, the carton will be inverted to make a package as shown in Fig. 14, with the workpieces or patties 45 visible through the window 46'. In each operation of the machine, a complete filling of workpieces will be deposited on a blank. During the retractive movement of the mould slide, the operator will remove the blank and erect and close it about the workpieces to the form of Fig. 14, leaving the next successive blank exposed to receive a subsequent charge of workpieces in the next cycle.

The cycling of the machine is manually initiated by means of control lever 60 which is shown in full lines in its normal position in Fig. 4 and appears in broken lines in the position in which it is manually depressed by the operator to initiate the cycle. As shown in Fig. 8, the lever 60 has a loose pivotal connection at its inner end to the valve housing 61, such connection being provided by passing a screw 62 loosely through an aperture in the lever 60. Air applied under pressure through the pipe 63 is admitted through vent 64 to a cylinder 65 in which there is a piston 66 which not only supports the lever 60 but also supports the valve piston 67 in the valve cylinder 68.

Valve cylinder 68 has an air pressure inlet port at 69, a vent at 70 and a controlled air port at 71. In the normal elevated position of the valve piston 67 shown diagrammatically in Fig. 10, the duct 72 through the valve piston 67 maintains the controlled port 71 in communication with the vent port 70. When the lever 60 is depressed from the position shown in Fig. 10 against the pressure of the air in cylinder 65, the valve duct 73 places the pressure port 69 in communication with the controlled port 71 to deliver pressure through a line 75 to the cylinders 76 and 77. Having thus manipulated the lever 60, the operator will release the lever and the machine will thereupon complete a cycle of operation automatically without further attention on the part of the operator.

The pressure thus admitted to the cylinder 76 will act on the piston 78 to advance valve piston 79 and valve cylinder 80 from the retracted position shown. Valve cylinder 80 has a pressure port 81 constantly supplied with pressure through line 82 from the air supply line 63. It has a vent at 83 and controlled ports 84 and 85. There are cross connecting ducts 86 and 87 in the piston which, in the normally retracted position of the valve piston 79 place pressure port 81 in communication with controlled port 83 and place vent port 83 in communication with controlled port 84. The controlled port 84 communi-

cates through duct 89 with port 91 of a reversing valve cylinder 92 equipped with a valve piston 93 normally retained in retracted position of Fig. 10 by means of a compression spring 94 acting on the valve stem 95. Duct 89 also communicates through branch duct 96 and cross-connection duct 97 with the end portions of the cylinders 98 and 99 in which the pistons 100 are reciprocable for the operation of the mould slide 30 or any substituted slide 300. The pistons 100 have piston rods 101 connected together by a cross head 102 detachably screwed to the rear end of the slide. One of the piston rods has a valve actuator 104 which, in practice, takes the form of a collar shown in Fig. 1 but is diagrammatically illustrated in Fig. 10 as a laterally projecting arm. This valve actuator is so positioned that in the extreme inner position of the slide 30, it will engage the valve stem 95 to move the valve piston 93 from the retracted position of Fig. 10 to an advanced position in which the air supply connections through the controlled port 105 of valve cylinder 92 will be reversed. Port 105 normally communicates through valve duct 106 with vent 207. When the piston 93 is advanced by the operation of valve actuator 104, the cross duct 103 of the piston places the control port 105 in communication with duct 91, whereby pressure is admitted to the line 107 leading to the port 108 of knockout valve cylinder 109.

In the illustrated retracted position of the valve piston 110, the valve cylinder 109, the cross duct 111 in piston 110 place port 108 in communication with controlled port 112 from which duct 113 leads to the lower end of ram cylinder 114 in which piston 115 is mounted on the plunger 42 of the cross head 41 which carries the knockout dies 40. In the position in which the parts are illustrated, the pressure communicated to the various valve arrangements disclosed has elevated the piston 115 in cylinder 114 so that the knockout dies are in retracted position. At the same time, the upper end of knockout cylinder 114 is vented through line 116 and valve duct 117 and vent port 118 of the knockout valve cylinder 109.

However, as already noted, the illustrated position of piston 110 is not the position in which such piston is disposed in cylinder 109 at this stage. Operation of the manual control lever 60 and admission of pressure to line 75 has not only elevated piston 78 in cylinder 76 but has elevated piston 119 in cylinder 77, whereby valve 110 has been advanced from the position shown in Fig. 10 to a position in which the cross connection ducts 120 and 121 are effective to connect line 116 to the port 108 and vent duct 118 with port 112. Thereby the vent 118 is not connected with line 116 but with line 113.

Accordingly, at the time the valve piston 93 is displaced in cylinder 92 by the movement of the mould slide, the knockout valve connections are such that the pressure admitted to the line 108 is communicated through line 116 to the upper end of cylinder 114 to move the knockout die plungers 40 downwardly to discharge the workpieces onto the package blanks, as already described.

When such discharge is complete, a valve actuator 125 carried by plunger 42 strikes the valve stem 126 to depress it against the spring 127 whereby to displace the piston valve 128 in cylinder 129 from the retracted position in which the parts are illustrated in Fig. 10. In the illustrated retracted position, the vent port 130 communicates through valve duct 131 with line 132 leading to the valve actuating cylinder 133. In the advanced position of the piston 128, the cylinder port 134, supplied with pressure through line 116, is placed in communication by means of the valve duct 135 with line 132 through the controlled port 136. The resulting pressure communicated through duct 132 to the valve-actuating cylinder 133 displaces the piston 137 back to the retracted position in which it is illustrated, thereby moving the valve 110 to break the pressure connection to line 116 and to re-

store pressure connection to line 113, whereby the knock-out plungers 40 are retracted.

The line 113, now subject to pressure, has a branch 140 leading to the port 141 of valve controlled cylinder 142. The piston 143 in this cylinder is normally advanced by compression spring 144 about the stem 145, and is in the path of retractive movement across port 141 so that the retractive movement of the knockout plungers 40 will ultimately move the valve piston 143 to the position illustrated in Fig. 10 wherein the cross connection duct 147 places port 141 in communication with the control port 148 leading to line 150. In the normal position to which valve piston 143 is advanced by its spring 144, the cross connection duct 151 of the piston registers with port 148 and with vent port 152 whereby line 150 is vented.

Admission of pressure to line 150, consequent upon full retraction of the knockout dies 40, supplies pressure to valve controlled cylinder 153 to advance the piston 154 therein to the position in which it is illustrated in Fig. 10. This will vent lines 89 and 96 and will admit pressure to line 90 which leads to the outer ends of cylinders 98 and 99, whereby the slide 30 will be retracted to its original position, thus completing the cycle in readiness for initiation of another cycle by a subsequent manipulation of the control lever 60 by the operator.

Reference characters used on the parts shown in the diagram of Fig. 10 have been applied, where applicable, to the mechanical structure. However, it should be noted that the mechanical structure is not necessarily identical with the diagram and, since the mechanical structure of the valves is not claimed per se, it is unnecessary to the present application that it be described in detail.

The several vents are desirably connected to pass through a discharge stack 160 which may also comprise a silencer. The cross connecting ducts which, for the purposes of the diagram, are shown within the valve pistons 79 and 110 may, in practice, be built into the cylinders rather than the piston 79. The actual structure of typical valves will be found in Figs. 7, 8 and 9.

The slide-operating cylinder and piston assemblies are desirably mounted at the sides of the channel-shaped housing in which the slides reciprocate, the cylinder heads being screwed to the flanges 13 and 14 as best indicated in Figs. 1 and 5. Valve cylinders, separately illustrated in the 45

diagram, Fig. 10, may actually comprise bores as shown, for example, in the case of the cylinders 92, which, in practice, constitute a bore at the head of the cylinder 98, as shown in Fig. 7.

5 As in the device of application 384,200, the knock-out or ejector dies are desirably heated to prevent the material from adhering thereto. This is accomplished by the provision in the cross head 41 of a resistance element shown only in dotted lines at 165 in Fig. 1 and having electrical wiring connections 166 as indicated in Fig. 2.

10 I claim:

15 1. A method of packaging patties in a windowed box, which method comprises stacking a plurality of inverted blanks from the topmost of which blanks such box may be formed, moulding a series of patties, ejecting the moulded patties from the mould onto a windowed face of the topmost inverted blank, erecting and closing said topmost blank about the series of patties discharged onto such face to form a box and thereafter inverting the box 20 to disclose the patties through the windowed face upon which they are deposited.

25 2. A method of producing a package of patties, such method comprising the steps of reciprocating an apertured mould between one position in which the mould is aligned with a source of patty material and in which the mould apertures are filled and another position in which the filled mould overhangs an inverted box blank, ejecting patties from said mould onto said box blank in a direction transverse to the direction of mould reciprocation, withdrawing the emptied mould from over the box blank and thereafter forming the box blank about said patties.

30 3. A method of producing packages of patties, such method comprising the steps of stacking windowed box blanks in inverted position, forming patty material into 35 patties in a mold, depositing molded patties directly from the mold onto the successive box blanks which are uppermost in the stack, and forming respectively about patties deposited thereon from said mold, the successively uppermost box blanks upon which the patties are deposited.
